DRILL PIPE PROTECTOR ASSEMBLY

Walter G. L. Smith, Los Angeles, and Adelbert M. Graham, Beverly Hills, Calif.; said Graham assignor to said Smith

Application July 19, 1941, Serial No. 403,146

3 Claims. (Cl. 308—4)

This invention relates to drill pipe protector assemblies for use on sections of a string of well drilling pipe to protect the pipe from wear against the well casing or the side walls of the well in the operation of a rotary well drilling rig.

It has been customary to make the drill pipe protectors in the form of rings of rubber or other resilient material and to secure them upon the pipe in positions fixed both longitudinally and circumferentially of the pipe. It is of obvious advantage to prevent movement of the drill pipe protector longitudinally of the pipe, as otherwise the protector under the action of gravity will move downward to the nearest coupling. The disadvantage of a circumferentially fixed mounting of the protector upon the drill pipe has been recognized. The drill pipe in rotary drilling is slowly rotated on its axis. A protector circumferentially fixed upon it, when thrown by the pipe against the sides of the well, is subject to a glancing blow which is obviously more destructive of the protector than is a blow delivered perpendicularly to the protector with no tangential component. Even when the drill pipe is not rotated, if it swings outwardly, throwing the protector against the sides of the well, it is apparent that either because of irregularities in the surface of the side walls of the well or because the protector may be thrown at an angle against the side walls, the force of the impact will have a destructive tangential component.

The tangential component of a blow against the protector will be less destructive if the protector is free to rotate upon the pipe. Part of the force of impact may then be used to spin the protector upon the pipe instead of having to be absorbed by the resilient material of the protector. However, the problem of mounting a protector rotatably upon the drill pipe presents two major difficulties. The bearing between the rotatable protector and the pipe affords lodgment for the mud fluid used in the drilling operation, and this mud fluid cuts through the drill pipe with extreme rapidity. The second difficulty lies in the provision of a means for preventing movement of such a rotatable drill pipe protector longitudinally of the pipe, which is practicable and will stand up under the severe conditions which obtain in a well during the well drilling operation.

A drill pipe protector assembly of this invention has the advantages attendant upon a rotative resilient ring and has not the disadvantages of being the cause of a rapid cutting of the pipe radially beneath the ring and of having an in-

effective short-lived longitudinal retaining means.

It is one object of the invention to provide a drill pipe protector assembly which will stand up under the heavy blows to which it is subjected.

It is another object of the invention to provide in a practical form a rotatable resilient protector.

It is another object of the invention to provide a protector which will be both longitudinally stationary and circumferentially rotatable with respect to the pipe.

It is another object of the invention to provide in a rotatable drill pipe protector assembly a bearing for the rotating ring or spinner into which the mud fluid cannot enter to cut through the wall of the drill pipe.

It is another object of the invention to provide a convenient method for installing a drill pipe protector assembly comprising a drill pipe section, two spaced metal flanges on the pipe section, an inner annular resilient body adapted to be shrunk on the pipe between the flanges, and an outer annular resilient body rotatively mounted in longitudinally fixed position between the flanges and upon the inner body.

Further objects and advantages of the invention will be made evident throughout the following part of the specification.

In the drawing, which is for illustrative purposes only:

Fig. 1 is a perspective view of a drill pipe protector assembly embodying this invention, the drill pipe being shown in fragmentary view;

Fig. 2 is a longitudinal section of the drill pipe protector assembly shown in Fig. 1;

Fig. 3 is a longitudinal section of the base of the drill pipe protector assembly;

Fig. 4 is an end view of the base;

Fig. 5 is a longitudinal sectional view of the rotatable ring or spinner of the drill pipe protector assembly;

Fig. 6 is an end view of the spinner;

Fig. 7 is a longitudinal sectional view of the base shown on a storage or handling mandrel;

Fig. 8 is a longitudinal sectional view of the spinner shown on a storage or handling mandrel;

Fig. 9 is a longitudinal sectional view partly in elevation of a modified form of the drill pipe protector assembly of this invention; and

Fig. 10 is a longitudinal sectional view partly in elevation of another modified form of a drill pipe protector assembly of this invention.

A drill pipe protector assembly of this invention comprises a drill pipe section 11, two steel

flange rings 12, a protector base 13, and a spinner 14.

The flange rings 12 are preferably of generally rectangular cross section and of an inside diameter to fit snugly over the pipe section 11. An outer end face 15 of each flange ring is inclined to the axis of the pipe section to facilitate movement of the flange ring past objects in the well as the drill pipe is lowered into the well or elevated therefrom. The flange rings are annularly welded to the pipe section 11 at 16 and 17 with their inner end faces 18 spaced from each other for the disposition of the other elements of the pipe protector assembly.

The base 13 is preferably a one-piece ring or sleeve of rubber or other light resilient material of an inside diameter normally substantially less than the outside diameter of the pipe section 11 and of a length to extend over the space between the end walls 18 of the flange rings 12. It is expanded and shrunk upon the pipe section in a manner to be presently described, and because it is normally substantially smaller in diameter than the outside diameter of the pipe section, it tightly embraces and is immovably seated upon the pipe section.

The rotatable ring or spinner 14 has the shape shown in Figs. 5 and 6. Its outer edges are preferably beveled at 19 to enable it to more readily pass objects in the well as the pipe section is lowered into the well or elevated therefrom. It is somewhat shorter than the base 13, has normally an inside diameter slightly larger than the outside diameter of the base 13 when the latter is seated in position upon the pipe section, and has an outside diameter substantially greater than the outside diameter of the flange rings 12, providing for its engagement with the well casing or walls of the well structure.

To install the spinner 14, it is expanded sufficiently to pass over either of the flange rings 12 and is thereafter allowed to contract to its normal diameter, loosely fitting upon and rotatably engaging the base 13.

Both the base 13 and the spinner 14 are preferably manufactured in accordance with the invention which is the subject matter of an application for patent by Adelbert M. Graham, one of the joint inventors herein, Serial No. 389,759, filed April 22, 1941. In accordance with the invention of that application, one-piece cylindrical rubber pipe protectors are made by spirally winding upon a mandrel a thin sheet of hot compounded uncured rubber taken directly from the final roll of a calender roll machine. The laminated cylinder thus formed is cured on the mandrel in the vulcanizing furnace, and while still on the mandrel is turned down to the proper diameter and cut to the proper length. It is then removed from the mandrel, and upon removal shrinks to a slightly smaller diameter both as to its bore and as to its outer cylindrical surface. The molecules of each lamina are in a condition to set up circumferential stresses tending to still further shrink the protector, and the laminae are bonded to each other by an adhesive relationship resulting from the superimposing of the spiral convolutions while in a hot "tacky" condition. The finely spaced lines 20 on the drawing indicate the bonding joints between laminae.

In installing the base 13, it is expanded by means of a machine such as shown in the application of Adelbert M. Graham, Serial No. 346,615,

filed July 20, 1940, and transferred to a storage or handling mandrel 21 which may be for convenience termed a "holder," such as is also described in the application of Adelbert M. Graham, Serial No. 346,615. In Fig. 7, the base is shown thus mounted on the holder 21, the holder being formed of a thin-walled pipe. By comparing the base shown in Fig. 7 with that shown in Fig. 3, it will be observed that the inside and outside diameters of the base have been greatly increased, and the wall thickness and length of the base have been decreased.

The spinner 14 is similarly expanded and placed upon a holder 22 of a larger diameter than the holder 21. The base and spinner are now ready for assembly upon a section of drill pipe.

During the drilling operation and after the kelly has been disconnected from the uppermost section of the drill pipe, or when the pipe sections are on a pipe rack or otherwise disposed singly or in double or treble stands, the holder 21 with the base 13 mounted thereon is telescoped over one of the flange rings 12 together with hydraulic means assembled with the holder 21, such as shown in the above-mentioned application, Serial No. 346,615, of Adelbert M. Graham. The holder 21 has a bore of sufficient size to pass over any sleeve coupling or tool joint which may be secured to the drill pipe as well as over the flange rings 12. When the holder 21 and hydraulic mechanism assembled thereon are in such a position that the base 13 registers with the space between the two flange rings 12, the hydraulic means is operated to slide the holder relative to the base 13, allowing the base to contract and closely grip the section of drill pipe 27 between the two flange rings. The holder 21 and its assembled hydraulic mechanism are then passed over the flange ring 12 and removed from the end of the drill pipe section.

The spinner holder 22, which like the holder 21 has a bore diameter larger than the outside diameter of the flange rings 12, is then passed over one of the flange rings until the spinner 14 mounted upon it is longitudinally opposite the base 13; the hydraulic mechanism associated with the holder 22 is operated to deposit the spinner 14 on the base with its end faces between the end walls 18 of the flange rings 12 and with its bore surface loosely engaging the outer surface of the base 13. The length of the spinner 14 is such as to provide small longitudinal clearance spaces between its end walls and the end walls 18 of the flange rings 12, and its inside diameter is such as to provide a small radial clearance between the spinner and the base 13.

While the mud fluid used in the drilling operation may pass through the small clearance spaces at the ends of the spinner to the clearance space between it and the base, the abrasive solid material of the mud fluid will not appreciably cut away either the spinner or the base, because of the resilient character of these bodies. On the other hand, the base, tightly fitting upon the drill pipe, prevents entrance of any of the mud fluid between the base and the pipe section, thus eliminating any cutting of the walls of the pipe section.

The spinner is prevented from longitudinal displacement along the pipe section by means of the flange rings 12. In wells in which the conditions are such that bodies of rubber become soft or spongy or structurally deteriorate so that they

become subject to extreme deformation or laceration, flange rings of rubber, such as are disclosed in the application of Walter G. L. Smith, Serial No. 394,145, filed May 9, 1941, for a Drill pipe protector, are ineffective after a period of use to retain the spinner 14 in proper position longitudinally of the pipe section. Under conditions of this kind, steel flange rings such as are disclosed in this application have an advantage over those of rubber disclosed in the above-mentioned application of Walter G. L. Smith, Serial No. 394,145.

The laminated character of the base gives it a tighter grip upon the pipe than is true of a base fabricated without laminae.

While the base is preferably formed as hereinabove described, it is apparent that it need not be laminatedly constructed and that it may even be made of other than rubber or resilient material without losing some of the advantages of this invention. It also need not be a one-piece body, but may be made of two semicircular halves or of other sections suitably secured to form a cylindrical bearing member for the spinner 14.

Figs. 9 and 10 illustrate other forms which the invention may take.

In Fig. 9 each of the flange rings 12a is a split ring, the two semicircular halves thereof being secured by welding joints 25. Each of the semicircular halves is annularly welded to the pipe section 11a in the same manner as that in which the flange rings 12 are annularly welded to the pipe section 11, as shown in Fig. 2. A split ring 12a may be used where it is difficult or impossible to telescope a one-piece ring like the flange ring 12 over the end of the pipe section 11.

In Fig. 10 the flange ring 12b takes the form of a split ring, the two semicircular halves of which are clamped tightly together upon the pipe section by means of bolts 26. This form of flange ring also may be used where it is difficult or impossible to pass a one-piece annular flange ring over the end of the pipe section.

The flange rings 12 for longitudinally retaining the spinner in place on the pipe section may take other forms without departing from the spirit of the invention, and, in fact, the end faces of couplings or other annular elements fixed to the pipe section for some other purpose may be utilized to provide end thrust bearing shoulders for the purpose of retaining the spinner longitudinally in place upon the pipe section.

While the flanges in the specific embodiments of the invention herein set forth have been described as welded or otherwise secured to a pipe section or joint, it is apparent that these flanges may alternatively be secured to any drill pipe element, such as a tool joint or collar, provided that these pipe elements are adapted for such securing. It is also apparent that the flanges may be integrally formed upon a pipe element when the pipe element is fabricated. Such

flanges may well be integrally formed on collars and joint lengths specially designed for carrying spinner protectors.

The invention is not to be limited to any specific embodiment herein shown, but is to be given the scope defined in the appended claims.

We claim as our invention:

1. In a drill pipe protector assembly, the combination of: a metal drill pipe element; a rubber bearing sleeve contactually surrounding and immovably secured to said drill pipe element; two metal flange rings contactually surrounding and immovably associated with said pipe element, one at each end of said sleeve, said flange rings being of substantially greater outside diameter than said sleeve; and a rubber protector ring rotatably mounted on said sleeve between said flange rings, said protector ring having an inside diameter slightly greater than the outside diameter of said sleeve, having an outside diameter substantially greater than that of said flange rings, and being slightly shorter than said sleeve, the bore surface portion of said protector ring and the peripheral surface portion of said sleeve being of resiliently compressible rubber and rotatively in contact with each other.

2. In a drill pipe protector assembly, the combination of: a metal drill pipe element; a rubber bearing sleeve shrunk on said drill pipe element; two metal flange rings welded to said pipe element in end engagement with the ends of said sleeve respectively, the outside diameter of said flange rings being substantially greater than that of said sleeve; and a rubber protector ring rotatably mounted on said sleeve between said flange rings, said protector ring having an inside diameter slightly greater than the outside diameter of said sleeve, having an outside diameter substantially greater than that of said flange rings, and being slightly shorter than said sleeve, the bore surface portion of said protector ring and the peripheral surface portion of said sleeve being of resiliently compressible rubber and rotatively in contact with each other.

3. In a drill pipe protector assembly, the combination of: a metal drill pipe element; a rubber bearing sleeve shrunk on said drill pipe element; two steel flange rings immovably associated with said pipe element in end engagement with the ends of said sleeve respectively; and a rubber protector ring projecting radially beyond said flange rings and rotatably mounted on said sleeve between said flange rings with a small cylindrical bearing clearance between said protector ring and sleeve and with a small end bearing clearance between said protector ring and said flange rings, the bore surface portion of said protector ring and the peripheral surface portion of said sleeve being of resiliently compressible rubber and rotatively in contact with each other.

WALTER G. L. SMITH.
ADELBERT M. GRAHAM.
